Inventor:
Claude L. Post
By Frie & Frie Atty's.

UNITED STATES PATENT OFFICE.

CLAUDE L. POST, OF CHICAGO, ILLINOIS.

ENVELOP FEEDING AND HANDLING DEVICE.

1,337,266.

Specification of Letters Patent. Patented Apr. 20, 1920.

Application filed March 13, 1919. Serial No. 282,300.

To all whom it may concern:

Be it known that I, CLAUDE L. POST, a citizen of the United States, residing at Chicago, in the county of Cook and State 5 of Illinois, have invented certain new and useful Improvements in Envelop Feeding and Handling Devices, of which the following is a description.

My invention relates to improvements in 10 envelop feeding and handling devices, and more particularly to mechanism designed for the printing of return addresses or other matter on envelopes.

An object of my invention is to provide a 15 press with means for feeding envelopes from a magazine to printing rollers or the like by turning the envelop flaps in such manner as to be successively engaged by said rollers.

20 A further object is to provide a cam-controlled finger for successively engaging the flaps of envelopes stored in a magazine and turning said flaps into engaging position with feeding rollers, whereby the envelopes 25 are successively withdrawn from said magazine for any purpose.

And a further object is to provide printing rollers of such a form as to permit envelop flaps to be turned on the fold thereof and be engaged by said rollers in quick succession. Other objects will appear hereinafter.

With these objects in view, my invention 35 consists in the novel construction, combination, and arrangement of parts all as will be hereinafter described, and more particularly pointed out in the appended claims.

An embodiment of my invention is shown 40 in the accompanying drawings representing a printing press, forming a part of the specification, and in which—

Figure 1 is a side elevation of my improved printing press, showing an envelop 45 magazine removably secured thereto;

Fig. 2 is a top plan view of the press, showing the general arrangement of the operating parts;

Fig. 3 is a detail plan section taken on 50 line 3—3 of Fig. 1, showing an envelop support employed on said magazine;

Fig. 4 is a view showing the flap side of an ordinary envelop;

Fig. 5 is a vertical longitudinal section 55 of the press taken on line 5—5 of Fig. 3;

Fig. 6 is a vertical transverse section taken on line 6—6 of Fig. 1, a portion of the printing rollers being shown in elevation; and

Figs. 7, 8 and 9 are diagrammatic views 60 showing several stages in the envelop feeding operation.

The preferred form of construction, as shown in the drawings, comprises a frame having side members 1 and 2, the latter 65 being provided with a rearwardly extending arm 3, as shown in Figs. 1 and 2. Forwardly extending arms 4 are provided to support an envelop magazine 5, which is held in position on said arms by means of 70 upwardly extending teeth 6. Said magazine is also provided with downwardly extending pins 7, which facilitate positioning thereof on arms 4.

The magazine 5 comprises a bottom 8 75 for supporting the body or pile of envelopes 9, there being an opening 10 in said bottom for permitting the envelop flaps 91 to drop slightly relative to body 9, which will be clear by reference to Fig. 5. The shape 80 of opening 10 corresponds more or less to the shape of an envelop flap, with the exception of a recess 11 which is provided to make clearance for a finger 12, the function of which will be described hereinafter. 85 The rear wall 13 of the magazine 5 projects downwardly a sufficient distance to retain envelopes 9 in said magazine when an envelop is being acted on by the finger 12. Magazine 5 further comprises walls 14 and 90 15, as shown in cross section in Fig. 3, for positioning the front corners of the envelopes contained in the magazine, the openings between the magazine walls being of use in enabling one to determine how many envelopes are stored in the magazine. 95

A drive shaft 16 is journaled in frame 1 and provided with a driving pulley 17 and a driving gear 18, as shown in Fig. 6. A driven shaft 19 is also journaled in frame 100 1 and arranged above shaft 16 and parallel therewith, shaft 19 carrying a driven gear 20 which meshes with gear 18, whereby said shafts are revolved at the same speed but in opposite directions. 105

A crank 21 is secured to shaft 16 by means of a set screw 22, and is provided with a crank pin 23 for reciprocating a connecting rod 24, as shown in Fig. 4. The rearward end of the connecting rod 24 is pivoted to 110

a link 25 extending downwardly from arm 3 and pivoted thereto as shown in Figs. 1 and 3. A horizontally movable connecting rod 26 is also pivoted to link 25 and is actuated thereby for moving finger 12, which is secured to an oscillating block 27 carried at one end of a laterally extending arm 28, which extends inwardly from the forward end of rod 26, as shown in Fig. 2. Secured also to block 27 is a rearwardly extending cam 29 which is guided in its movement by means of a transversely extending frame rod 30, the weight of finger 12 and cam 29 being sufficient to maintain said cam in contact with rod 30 throughout the travel thereof in either direction. Shafts 16 and 19 form a part of feeding and printing rolls 31 and 32, respectively, these rolls being surmounted by a pair of ink rolls 33 which carry an idler 34 for distributing ink thereon. Rolls 33 and 34 are journaled in the frame side members 1 and 2, as shown in Fig. 6, said roll 34 also being free to move endwise, whereby ink supplied to rolls 33 is uniformly distributed thereover.

The lower printing roll, or if desired both the rolls, are provided with feeding arcs 35 intermediate the ends thereof, and roll 32 is provided with a type block 36 for intermittent coöperation with a platen 37 having a tympan sheet 38.

The operation of the machine is as follows:

Assuming that ink has been supplied to the rolls 33 and that the finger 12 is positioned as shown in Fig. 5, then upon starting the machine the point of said finger will move to the left over flap 91, as shown in Fig. 7. Further movement of finger 12 to the left will effect a swinging of flap 91 on the axis or fold thereof, so that by the time finger 12 reaches the position as shown in Fig. 8, said flap will assume substantially a vertical position. It will be noted in this figure that the point of finger 12 has dropped somewhat in order to maintain contact with flap 91 and to prevent its punching the flap at its juncture with the body of the envelop. Said drop of the finger 12 is effected by the curvature of cam 29, as clearly shown in the several figures. The position of finger 12 when at the limit of the movement thereof to the left is shown in Fig. 9, in which figure flap 91 is shown just as it is engaged by the feeding means 35. The engaged flap will now be fed through the printing rolls, and when the body of the envelop is reached, the type block 36 will register with platen 37 and accomplish the printing operation. It will be noted that the arc of movement of the free edge of flap 91 projects into the arc of movement of feeding arc 35, but that interference with the latter is prevented by the cut away portion which forms the proper

clearance for the flap movement. After the printing has taken place, the envelops being fed through arc 35, are ejected therefrom, as indicated in Fig. 5.

While the free edge of flap 91 is shown normally spaced from the body of the envelop 9, for clearness of illustration, said flap may be fairly close to the body of the envelop, since the point of finger 12 is very thin and capable of entering recess 11 and traversing the lower side of the envelop before flap 91 is reached, whereupon the latter is reliably engaged and pressed downwardly as hereinbefore described.

While I have illustrated and described the preferred form of construction for carrying my invention into effect, there might be various changes and modifications without departing from the spirit of the invention. I therefore do not wish to be limited to the precise details of construction as set forth, but desire to avail myself of such variations and modifications as come within the scope of the appended claims.

Having thus described my invention, what I claim as new and desire to secure by Letters Patent is:

1. A device of the kind described comprising a pair of feeding rolls having co-operating feeding arcs, an envelop magazine arranged adjacent said rolls having a discharge opening through which envelop flaps normally project, and means for turning said flaps into engaging position with said feeding arcs, there being clearance between the ends of said arcs permitting such movement.

2. An envelop handling device comprising a driving roll and a driven roll, coöperating feeding arcs arranged on said rolls, a type block on one roll and a coöperating platen on the other, an envelop magazine having a discharge opening therein, and means for successively engaging envelop flaps projecting through said opening with said feeding arcs.

3. An envelop handling device comprising a driving roll and a driven roll, feeding arcs on said rolls arranged for intermittent co-operation, a type block on one roll and a co-operating platen on the other, said type block and platen being spaced from said arcs, an envelop magazine having a discharge opening adjacent said arcs, and means for successively engaging envelop flaps projecting through said opening and turning the same into engagement with said arcs.

4. An envelop handling device comprising a pair of coöperating printing rolls, feeding arcs on said rolls arranged for intermittent registration, an envelop magazine having a discharge opening adjacent said rolls, and a finger in operative relation with said rolls for successively engaging envelop flaps posi-

tioned in said opening and turning said flaps on the fold thereof into engagement with said arcs, there being clearance between the latter for permitting such turning movement.

5. An envelop handling device comprising a pair of printing rolls, feeding arcs on said rolls arranged for intermittent coöperation, a magazine having envelopes therein and a 10 discharge opening adjacent said rolls, and a cam-controlled finger for successively engaging envelop flaps positioned in said opening and turning said flaps on the fold thereof into engagement with said arcs.

15 6. An envelop handling device comprising a pair of feeding rolls, provided with co-operating feeding arcs arranged thereon, and co-operating printing means arranged in proximity thereto, in combination with an 20 envelop magazine arranged to receive the envelopes therein with the flaps positioned on the lower side thereof, with the flap edge forward, said magazine provided with a discharge opening adjacent to arcs of the feeding 25 rolls, a finger arranged to move in synchronism with the feeding rolls and intermittently engaging and turn the flaps of the envelopes into engagement with the feeding arcs thereof, and means for operating said 30 finger.

7. In an envelop handling device, a pair of rolls comprising a type block, a platen and feeding arcs, a magazine having envelopes therein with their flaps turned downwardly, there being a discharge opening in said magazine adjacent said arcs for the successive reception of said flaps, and a cam-controlled finger for engaging and turning said flaps on the fold thereof into successive 35 engagement with said arcs, the angular position of said type block being such as to contact with the body of the envelopes after said flaps have been fed through said arcs.

40 8. In an envelop handling device, the combination with a pair of printing rolls comprising feeding arcs, ink rolls co-operating with one of said rolls, an envelop magazine having a discharge opening slightly larger than the flaps of envelopes provided 45 therein, said opening being adjacent the contacting point of said arcs; there being clearance space between the ends of one arc for permitting the envelop flaps to swing on the fold thereof into engagement with 50 said arcs, and a finger for successively effecting such movement of said flaps.

55 9. In a printing press, the combination with a pair of printing rolls in geared relation, of feeding arcs on said rolls arranged 60 for intermittent coöperation, a magazine containing envelopes having a discharge opening at the lower end thereof in front of said arcs, an envelop flap being normally positioned in said opening, a finger, and

means for moving said finger into engagement with said flap and thence downwardly, rearwardly and upwardly turning said flap on the fold thereof into engagement with said arcs.

65 10. An envelop printing device comprising an envelop magazine arranged to support a plurality of envelopes in a superimposed pile flap down, and a reciprocating and transversely moving finger adapted to engage beneath the flap of the lowermost envelop and bend the flap downward and backward on its engagement with the body of the envelop as a center, in combination with gripping mechanism arranged to engage the extended flap and draw the envelop from beneath the pile, and coöperating printing means for printing the face of the envelop during its said movement.

70 11. An envelop printing device comprising an envelop magazine arranged to support a plurality of envelopes in a superimposed pile flap down, and a reciprocating transversely movable finger adapted to engage beneath the flap of the lowermost envelop and bend the flap downward and backward on its engagement with the body of the envelop as a center, in combination with gripping mechanism timed to engage the extended flap, and printing means timed to impress the print on a desired part of the 75 face of the envelop during its passage.

80 12. An envelop printing device comprising an envelop magazine arranged to support a plurality of envelopes in a superimposed pile flap down, and a reciprocating and transversely moving finger adapted to engage beneath the flap of the lowermost envelop and bend the flap downward and backward on its engagement with the body of the envelop as a center, in combination with 100 rotatable gripping members, means for rotating said members, and printing mechanism coöperating with the gripping mechanism arranged to print the face of the envelop during its passage.

85 110 13. In a device of the kind described a pair of feeding rolls, one of said rolls having an arc thereof removed, providing a section for the reception of an envelop flap between the two, and means for operatively 115 rotating the rolls, in combination with an envelop magazine arranged to receive envelopes therein with the flaps on the lower side thereof and the flap edge forward, a discharge opening in the magazine to permit the unfolding of the flap of the envelop, a cam controlled finger arranged to successively engage the several envelopes' flaps, and turn the same downward through said opening and into the path of the feeding 120 rolls, and means for operating the cam.

14. In a device of the kind described, a pair of feeding rolls provided with coöp-

erating feeding arcs and means for operatively rotating the same, in combination with an envelop magazine arranged adjacent to said rolls having a discharge opening through which the envelop flaps normally project, a reciprocating finger arranged to successively engage the flaps of the envelop and turn the same into engaging position

with the feeding arcs of the rolls, substantially described.

In testimony whereof, I have hereunto signed my name in the presence of a subscribing witness.

CLAUDE L. POST.

Witness:

JOHN W. HILL.
